UNITED STATES PATENT OFFICE

133,696

DESIGN FOR A PRAYER TOKEN OR THE LIKE

Catherine M. Connolly, Chicago, Ill.

Application July 20, 1942, Serial No. 107,623

Term of patent 7 years

To all whom it may concern:

Be it known that I, Catherine M. Connolly, a citizen of the United States and residing at Chicago, county of Cook, and State of Illinois, have invented a new, original, and ornamental Design for a Prayer Token or the like, of which the following is a specification, reference being made to the accompanying drawing, forming a part thereof.

Fig. 1 is a front elevational view of the prayer token or the like showing my design;

Fig. 2 is a view in edge elevation of the same;
Fig. 3 is a top plan view of the same;

Fig. 4 is a sectional view taken in planes represented by line 4—4 in Fig. 1; and

Fig. 5 is a fragmentary sectional view taken in a plane represented by line 5—5 in Fig. 1.

I claim:

The ornamental design for a prayer token or the like, substantially as shown.

CATHERINE M. CONNOLLY.
